CLAIM

The ornamental design for a light fixture having a heat sink, as shown and described.

DESCRIPTION

FIG. 1 is a front perspective view depicting a light fixture having a heat sink showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear perspective view thereof.

The details shown in broken lines in the figures form no part of the claimed design of the light fixture having a heat sink.

1 Claim, 7 Drawing Sheets
